FUEL INJECTOR

Milford G. Chandler, Flint, Mich.

Application March 6, 1936, Serial No. 67,486

22 Claims. (Cl. 123—139)

This invention relates to liquid injecting apparatus that is especially useful in lubricating devices and in fuel injecting mechanism for internal combustion engines and the like.

5 One of the objects of the invention is the provision of a new and improved liquid injector having novel means for metering and delivering liquid charges of oil, fuel and the like.

10 Another object of the invention is the provision of a new and improved fuel injector of the plate type having novel means for preventing undue and unequal wear on the moving parts of the metering mechanism.

15 Another object of the invention is the provision of a fuel injector for a multi-cylinder internal combustion engine having new and improved metering mechanism provided with novel means for actuating said mechanism whereby 20 liquid fuel will be caused to flow through a common reservoir and be discharged through outlet passages, each served by more than one plunger.

25 Another object of the invention is the provision of a new and improved fuel injector having metering mechanism provided with novel means for preventing leakage of the fuel during the operation of the device.

30 A still further object of the invention is the provision of a new and improved liquid injector that is simple in construction, inexpensive to manufacture, easily assembled, efficient in operation, may be readily and easily adjusted to meet all requirements, is composed of few moving parts and that is not likely to become broken or get out 35 of order.

Other and further objects and advantages of the invention will appear from the following description taken in connection with the accompanying drawings in which:—

40 Fig. 1 is a side elevation of an internal combustion engine with parts broken away for the sake of clearness;

45 Fig. 2 is an end elevation thereof with parts in section and parts broken away;

Fig. 3 is a vertical section of the fuel injection on line 3—3 of Fig. 4;

Fig. 4 is a section on line 4—4 of Fig. 3;

Fig. 5 is a section on line 5—5 of Fig. 3;

50 Fig. 6 is a section on line 6—6 of Fig. 3 showing the cut-off disk in retarded position;

Fig. 6a is a section similar to Fig. 6 with parts broken away and showing the cut-off disk in advanced position;

55 Fig. 7 is a view similar to Fig. 6 but showing

the parts in a more advanced position from that shown in Fig. 6;

Fig. 8 is a view similar to that in Fig. 7 but showing the parts in a further advanced position;

Fig. 9 is a perspective view of the distributor 5 member;

Fig. 10 is a perspective view of the driving member;

Fig. 11 is a perspective view of a portion of the control mechanism with parts in section for 10 more clearly disclosing the device;

Fig. 12 is a perspective view of the cut-off element;

Fig. 13 is a perspective view of the driving pin;

Fig. 14 is a vertical section of the control 15 mechanism with parts broken away and showing the parts in the same position as that shown in Fig. 6a; and

Fig. 15 is a diagram showing the path of movement of one of the distributor discharge ports. 20

For convenience of illustration and description, the device is disclosed and will be described as being employed as a fuel injector for an internal combustion engine. While the device will be described as a fuel injector, it is understood 25 that it may be used as a liquid distributor in other relations, as for instance, it may be employed as an oil injector in lubricating devices.

Liquid fuel injectors for internal combustion engines as heretofore constructed have either 30 been unsatisfactory in their operations, or have required such accuracy or precision in the construction of certain parts of the distributor mechanism that the cost of their manufacture practically precludes their use in any except the 35 very highest priced engines.

The present invention seeks to remedy these difficulties by the provision of a comparatively simple, inexpensive injector that has the peculiar characteristics that the parts are so constructed 40 that extreme accuracy is not necessary on longitudinal dimensions and the operation of the device is such that wear on the distributing mechanism does not affect the seal but tends to improve it. 45

Referring now to the drawings, the reference character 10 designates a portion of a vehicle comprising an internal combustion engine 11 of any suitable construction for propelling the vehicle in the usual manner. This engine may 50 be of the usual or any well-known construction but for the purpose of illustrating the invention, it is shown as being an eight cylinder V-type motor provided with an intake manifold 12, having an air intake 20 provided with a conventional 55

throttle 13 therein, which is adapted to be operated by an accelerator rod 14, as is usual in such constructions.

The fuel injector is shown at 15, mounted on the motor in juxtaposition to the intake manifold 12, as is clearly shown in Figs. 1 and 2 of the drawings. The fuel injector is adapted to be operated from the cam shaft 16 of the engine by means of a bevel gear 17 mounted on said shaft, 10 which meshes with a corresponding bevel 18 mounted on the lower end of a shaft 19, the upper end of which has a detachable interlocking connection with the driving member 21 of the fuel injector as shown at 22 in Fig. 3 and as will presently appear.

The fuel injector comprises a casing or body portion 23. The casing 23 is secured to the upper wall of the air intake 20 above the air intake manifold 12 in any suitable manner as by cap screws 25 or the like, Fig. 1. The casing has a cylindrical chamber opening upwardly and a closure for the casing comprising a head 26 which is secured to and forms a part of the casing. The head is secured in position in any suitable manner as by means of the bolts or screws 30 as is usual in such constructions.

The head or closure 26 is provided with a plurality of fuel discharge passages 27 therethrough, see Fig. 3. These passages have corresponding ports 28, 28c, 28b, 28c, 28d, 28e, 28f and 28g, Fig. 15, one port for each cylinder, opening to the lower surface or face 40 of the head as more clearly shown in Figs. 3 and 6 of the drawings. A fuel intake passage 29 is also provided in the head through which fuel flows from a suitable fuel supply tank 31, shown diagrammatically in Fig. 2, into a reservoir 32 in the central portion of said head. Each of the fuel discharge passages is in communication with its respective cylinder 35 (see Fig. 2) by a tube or conduit 36, which is adapted to deliver charges of fuel into the intake passage 37 of the corresponding cylinder 35 in firing order, as will presently appear.

Suitable mechanism is provided for delivering metered charges of liquid fuel to the cylinders 35 of the engine. The construction which is selected to illustrate one embodiment of the invention will now be described.

This mechanism comprises a driving member 21 and a distributor member 49. The driving member 21 is rotatably mounted in the cylindrical chamber of the casing 23. This member is provided, on its lower surface, with one element of a clutch, as a slot or socket 38, Fig. 3, which is adapted to be detachably engaged by or interlocked with the other element of the clutch, as the angular projection 39 on the upper end of the drive shaft 19. By making the elements of the clutch separable, the fuel injector may be readily removed from the engine.

The bottom wall of the casing 23 is provided with an enlarged opening through which the clutch member 38 extends. The wall is also provided with an annular bearing member 41, of any suitable material as bronze or the like, in order to reduce the friction between it and the rotating driving member 21, which may be, and preferably is, of hard material.

The base 34 of the driving member 21, Fig. 10, 70 is concentric with the driving shaft 19 and is provided with an upwardly extending driving crank 42, which is mounted eccentrically of the base 34 and of the driving shaft 19. This driving crank is rigidly mounted on and turns with the driving member 21.

Surrounding the driving crank 42 is a ring member or annular elevation 43 concentric with the crank and movable therewith. This ring is provided with a cam face 44 on its upper face. The cam face 44 comprises a decline or cam surface 45 on one side of the driving crank 42 and with a corresponding incline or cam surface 46 on the side opposite the decline 45. The depressed or valley portion 47 of the cam is horizontal and the elevated portion 48 between the cam surfaces 45 and 46 is also horizontal. These cam surfaces operate the pump plungers of the distributor member as will presently appear. The driving member 21 is provided opposite the crank 42 with an arcuate upstanding counterweight 49 for counterbalancing the eccentric arrangement of the driving crank 42 and distributor assembly.

Rotatably mounted on the driving crank 42 is a distributor member 49, see Fig. 9. This member is provided with an axial opening 51 extending longitudinally thereof, which is adapted to receive a bearing bushing 52 (see Fig. 3), which in turn is rotatably mounted on the upper end 53 of the driving crank 42. The opening 51 in the distributor member 49 has its lower portion counterbored as at 53 and extends to a point adjacent to the upper surface of the distributor member 49 as is clearly shown in Fig. 3 of the drawings.

A plug 54 is inserted in the counterbore between the bearing 52 and the bottom of said bore, Fig. 3. This plug has a reduced portion extending through the opening 51 to a point flush with the upper surface of the distributing member and is also provided with a depending projection 55 which extends downward into an opening 56 arranged axially in the upper end of the crank member 42. A driving pin 57 extends in an axial opening 58 in the plug 54 for rotating the fuel control member 59 with the distributing member 49 as will presently appear.

The distributor member 49 comprises a plate member 62 on its upper portion which is adapted to engage the lower face of the head 26 and is provided on its lower portion with a piston supporting portion or member 63 which is connected to the plate 62, as by the cylindrical connecting portion 64, as is clearly shown in Fig. 9 of the drawings.

In order to save metal and facilitate assembly, the projection 63 is scalloped, each lobe or scallop 60 having a circular opening 65 therethrough, in which the plungers of a series of pump devices are adapted to be secured as will presently appear.

The plate 62 is provided with a series of ports or openings 66, 66a, 66b, 66c, 66d, 66e on its face, Fig. 9, which are arranged in a circle about the openings 51, and extend through the plate 62. These ports are in communication with recesses 67, Fig. 3, in the lower surface of the plate 62.

Suitable means are provided for withdrawing fuel from the reservoir 32 through the ports in the plate 62 and discharging the same through said ports and through the ports and passages in the head, into the intake passages 37 of the engine cylinders. In the form of the construction selected to illustrate one embodiment of the invention, pumping devices 68 are employed for this purpose.

The number of pumping devices 68 correspond to the number of ports in the plate 62 and these devices are in communication with the recesses 67 respectively. Since these devices are all alike, only one need be described.

As shown, a bushing 69 is inserted in the recess 67 and this bushing is provided with a bearing 71, curved in cross section, having an axial passage 72 in communication with the corresponding opening in the distributor plate 62. A cylinder 73, having an upper ball-like end, is mounted in the socket bearing 71 and extends downwardly therefrom. This cylinder is in permanent communication with the passage 72 and is provided with an annular flange 74, which is adapted to be engaged by a spring 75 for holding the same upwardly against the bearing 71 so as to form a gasoline tight joint. These springs also press the distributor member upwardly against the face 15 of the head whereby a fuel proof joint is provided between these two members. The piston 76 for the cylinder is provided on its lower end with a cross head 77, which is adapted to seat in a corresponding opening 65 in one of the scallops 60. The cross head 77 is adapted to be held in assembled relation by spring pressed pin 78 which is adapted to engage in a lateral opening 79 in the corresponding lobe or scallop 60. The opening 79 is of sufficient size to permit reciprocation of the piston 76. The piston is adapted to be reciprocated by the cams 45 and 46 and the spring 75, which holds the piston on the cams and cam plate during the movement of the distributor member 49. The spherical bearing 71, 30 on the bushing 69, will permit slight angular variation of the cylinder 73 whereby accuracy in the manufacture of the parts is eliminated. This arrangement will permit ready removal of the pumping devices for replacement or repairs.

35 It will thus be seen that when the distributor member is mounted on the eccentric driving crank 42, the same will revolve with the revolution of this crank.

The upper face of the distributor plate 62 is flat and engages the under flat face 40 of the head member 26. It is desirable that the relative movement between these two members be such as to insure a gasoline tight joint at all times and in order to do this, it is necessary that the 45 movable member be subjected to a compound movement because, with a single movement, such for instance as a rotational movement, alone, the faces are likely to become worn unevenly in annular grooves, as for instance, the zone containing the ports will wear faster than the adjacent metal and as a result, the fuel would likely not be prevented from flowing along the groove from one port to the adjacent ones. But with a compound movement, or a movement in two or more 50 directions, a lapping action may be obtained which will insure a perfectly smooth face at all times on both members. In the present construction, this lapping action is accomplished by 55 causing the distributor member to rotate while it is revolving. Any suitable means may be employed for this purpose. In the form of the construction shown, an annular member 81 is mounted in the upper end of the casing 23 and is limited in its downward movement by any suitable means as a ring 82, seated in an annular recess in the inner surface of the casing 23. This annular member 81 is slidably mounted within the casing and may be removed by first removing the head 26. It is positioned and held from rotation by a pin 50, Fig. 5.

The upper surface of the ring is so constructed that it is flush with the upper surface of the distributor member 49, which is below the top edge 75 of the casing, in the construction shown, and is

provided on its lower portion with an inwardly extending flange 83, which is provided with a plurality of teeth 84. The number of teeth 84 will preferably correspond with the number of cylinders of the engine and these teeth are adapted to be engaged by corresponding teeth 85 on the head of the distributor member 49 as clearly shown in Figs. 5 and 9 of the drawings. These teeth may be of any suitable form and contour but are preferably on the segment of a circle 10 whereby they will have a rolling contact with the intermeshing teeth 84 on the ring 81. Preferably the pitch circle of the teeth is of substantially the same diameter as a circle passing through the center of the ports in the distributor plate 62 whereby a maximum lag will be provided in the movement of that portion of the plate adjacent the engaging teeth at the instant the distributor member discharges a charge of fuel through the corresponding ports in the distributor plate as will presently appear.

For convenience of manufacture, the teeth 85 are formed by the walls of the recesses 67.

In the operation of the device thus far described, the distributor plate 62 will be revolved 25 in the direction in which the drive shaft 19 is turning and will, at the same time, be rotated about the drive crank 53 in the opposite direction and consequently the cams 45 and 46 and springs 75 will simultaneously operate the oppositely arranged pumping devices. It will also be seen that as the plate 62 rotates and revolves, the ports therein will alternately be connected with the reservoir 32 and with one of the discharge ports in the head 26, as shown in Figs. 6 to 8. 35

In Fig. 3, the pumping device 68 at the left of the figure is in communication with the reservoir 32 through the passages 67 and port 66a at this time. The piston for this pumping device is being moved downwardly by the spring 75 for drawing a charge into the passage 67 in rear of the plunger or piston 76. At the right of said figure, the ports 28d and 66d are in alignment and at this instant, the cam is forcing the piston 76 upwardly, forcing the fuel through the aligned ports 45 and the passage 27, into the intake of the appropriate cylinder of the internal combustion engine.

Appropriate means are provided for controlling the amount of fuel that may be sucked into the cylinder of the pumping device for each charge. 50 This mechanism will now be described.

It comprises a cut-off element 86 and suitable control mechanism. The cut-off element comprises a disk or plate 87 having a hub 88 extending upwardly therefrom. The hub is provided with an axial opening for receiving a pin 89 on which the cut-off element is caused to rotate by the driving pin 57 and on which it may be rotatably adjusted, as will presently appear. The 60 plate 87 has a segment 91 removed to form a port 90 as shown more clearly in Figs. 6, 7, 8 and 12 of the drawings. The disk is also provided with an arcuate slot 92 through which the driving pin 57 is adapted to extend. This slot permits the 65 adjustment of the disk for varying the amount of fuel flowing into the pumping device.

The adjustment of the cut-off element is effected by means of the control mechanism 94 which comprises a spool or body portion 95, Fig. 70 11, having an axial opening 96 and provided with an annular groove 97 extending about its intermediate portion. The lower portion of the spool 95 is provided with a plurality of vertical openings 80 through which the fuel may pass from 75

the receptacle 32 to the space below said spool. It is also provided with a radial keyhole slot 98 which is adapted to receive a corresponding head 99 on the upper end of the driving pin 57, which will cause the spool, and with it the plate 86, to revolve with the distributor member about the axis of the drive shaft. The bore or opening 96 in the spool is provided with a pair of cams or segmental threads 101 and 102 which are adapted 10 to be engaged by corresponding cams or segmental threads 103 and 104 on the hub 88 whereby when the spool is raised or lowered, the cooperating cams will cause a partial rotation of the plate 87 in one or the other direction depending upon whether the spool is moved upward or downward. When the spool is in one extreme position, the ports in the distributor plate, as they pass across the port 90, will be in communication with the reservoir 32 a maximum length of time and 20 will therefore receive a full charge of gasoline but when in the other extreme position, a minimum charge will be received by these ports. These adjustments are indicated in Figs. 6 and 6a in which the ports are in the same relative 25 position except the cut-off disk or element 86 is shown advanced in Fig. 6a. It will be seen from an inspection of Fig. 6a that as the distributor plate 82 rotates clockwise in its operation, the path of the succeeding port 66b will cut across 30 only a small segment of the port 90 and for only a portion of this movement will the corresponding piston be engaging the decline 45 of the cam whereby a minimum of fuel will be received by port 66b and succeeding ports. The spool is at 35 its lowermost position in Figs. 3 and 6 and is at its maximum elevation in Figs. 6a and 14. By adjusting the spool up or down the cut-off of the fuel may be adjusted to give the charge desired. The spool is adapted to be raised and lowered by 40 a lever 105 which is bifurcated and provided with a pivoted block 106, which in turn is adapted to engage in the annular groove 97 in said spool.

The lever 105 has a bearing 107 which is journaled in an opening 108 in the head 26. In order 45 that the variation in the amount of the charge and the amount of air supplied may be simultaneously controlled, the lever 105 and the lever arm 109 of the throttle 13 are connected in any suitable manner. In the construction shown, 50 which is for illustrative purposes only, a link 110 is employed for this purpose. Other types of linkage or connecting means may be employed as desired or as occasion may require.

A pair of set screws 120 and 130 may be provided for adjustably limiting the rocking movement 55 of the bearing 107.

In order that the plate 87 shall be properly held in its lowered position, a spring 111 is inserted between the upper end of the hub 88 and 60 the head 112 of the pin 89.

If desired, the intake passage 29 may be enlarged as at 113 and a filter 114 for the fuel inserted therein as shown more clearly in Fig. 4 of the drawings.

In order that there shall be greater uniformity 65 in the operation of the engine cylinders, it is highly desirable that each cylinder be served by a plurality of pumping devices. Such an operation is obtained by the present construction. This 70 arrangement is capable of wide variation.

For instance, if the number of teeth in the ring 81 be the same as the number of cylinders and be represented by n , and if the number of teeth on the distributor plate be the same as 75 the number of pumping devices and be repre-

sented by p , then in order to complete a cycle of operation, the distributor plate must revolve

$$\frac{L}{p}$$

times, where L is the least common multiple 5 of p and n . And since during this cycle, each cylinder is served once by a different pumping device during each revolution of the distributor mechanism, it follows that each engine cylinder 10 will be served by

$$\frac{L}{n}$$

pumping devices during each cycle of operation. Consequently, if $L=n \times p$, then each cylinder will 15 be served by all of the pumping devices during each cycle of operation.

In the present construction, the least common 20 multiple (L) of 8 and 6 (n and p) is 24. Consequently each cylinder will be served by $24 \div 8 = 3$ 20 different pumping devices and each pumping device will serve $24 \div 6 = 4$ different cylinders during each cycle of operation.

The operation of the complete device may be 25 briefly described as follows:

The rotation of the power shaft 19 will revolve the crank 42 and with it the distributor mechanism 49. This mechanism will simultaneously be rotated on the crank so that the ports in the plate 82 will alternately align with the ports in 30 the head and with the port 90 leading to the reservoir 32. The port 90 will be rotated by the threads or cams 101 and 102 once during each revolution in the same direction as the revolution of the distributor member whereby, as the 35 ports 66, 66a, 66b, 66c, 66d and 66e of the distributor plate are shifted inwardly by the eccentric movement of the crank 42, they will be caused to align with the port 90.

Assuming now that the ports are in the position shown in Figs. 3 and 6, the plunger 76 at the left of Fig. 3 is moving down about midway the cam 45 and is withdrawing a charge of fuel through the port 90 and port 66a, which is in alignment with the port 90 as shown in 45 Fig. 6. Fuel will continue to flow through the port 66a so long as it is unmasked by the plate 86; that is so long as it is in alignment with the port 90. The amount of the charge is controlled by the plate 86. The flow of fuel is cut off by this plate which may be adjusted in position by the accelerator in the usual manner. The plate 86 may be advanced or retarded for controlling the amount of the charge which is sucked 50 into the cylinder of the plunger and in the passage 67 above the plunger. Simultaneously with the sucking of fuel in through the port 66a, the piston or plunger 76 at the right of Fig. 3 is moving up the incline of the cam 46, the same being held against the incline by the spring 75 55 and is discharging its charge through the aligned ports 66d and 28d. The fuel charge, which is being sucked into the cylinder 73 of the plunger 76 at the left of Fig. 3, will likewise be discharged by the cam 46 when the port 66a is turned into 60 alignment with a discharge port in the head. 65

The parts are so constructed that at the time the fuel is being delivered by the plunger 76 through the aligned ports 28d and 66d, the port 66d is adjacent to the teeth 84. In other words, 70 the crank 42 has shifted the distributor plate to its maximum distance radially outward to cause the port 66d in the distributor plate to align with one of the ports in the head and at this time the port 66d is moving at a minimum 75

of velocity. Since the port $66d$ is substantially on the pitch circle of the teeth of the distributor plate, the plate may be considered as pivoting about the ports $28d$ and $66d$ when the same are in alinement. This arrangement is considered an important feature of the invention because it affords ample time for the discharge of the fuel without the provision of an elongated port.

By referring to Fig. 15, which shows a figure disclosing the path described by one of the ports of the distributor plate 62 , it will be seen that each of these ports describes a looped path 115 , each of the loops 116 indicating the travel of the port $66d$ while fuel is being discharged. The distance traveled in equal intervals of time by the port $66d$ of the distributor plate is indicated by the small circles $66d$ on Fig. 15. Each of the remaining ports of the distributor head describes a similar path.

From an inspection of Figs. 6, 8 and 15, it will be seen that the angular movement of the ports in the distributor plate, while they are in delivery position, are very much smaller than the angular movement of those ports of the distributor plate during the same interval of time while the charge is being sucked into the pumping device.

The lengths of the passages from the reservoir 32 to the cylinders of the pumping devices are preferably all of the same length and are extremely short. This is also considered an important feature because it insures a uniform charge for each of the pumping devices. If some of the passages were short and some of extended length, the charges would not be uniform because of the inertia of a longer column of fuel and also because of the greater amount of vaporization of the fuel in the longer tube which might relieve the vacuum on the suction stroke.

Preferably, though not necessarily, the lower face of the head 26 is of such diameter that the face plate 62 will overlap or extend radially outwardly beyond the head face at the points where fuel is being delivered. As a result of this arrangement, a maximum amount of pressure is applied to the portion of the distributor plate where the fuel is being discharged. Since the movement at this point is at its minimum, this arrangement does not result in objectionable or excessive wear of the moving parts. It does have, however, a decided advantage in preventing leakage of the fuel while it is being delivered. This arrangement is possible by the fact that a wide recess 140 , extending around the face 40 of the head 26 , is provided as shown in Fig. 3. This face may be scalloped to further increase the pressure on the exposed face and at the same time afford a wide bearing surface around each of the discharge ports.

It will thus be seen that a liquid injector has been provided in which a single cam is employed for operating a plurality of pumping devices, each of which serves a plurality of engine cylinders. It will also be noted that the compound movement of the distributor member not only permits a relatively slow movement of the discharge port while it is delivering fuel but that the engaging faces are continually lap-ground during the operation of the device, thus insuring against leakage of gasoline from one port to the other.

Furthermore, the variable cut-off mechanism is so arranged that when the port 90 of the variable cut-off disk 87 is in alinement with any of the intake ports in the distributor plate 62 , the

pressure of the fuel and the suction of the corresponding device will tend to firmly seat the cut-off disk on the distributor plate to prevent leakage around the cut-off disk and when the ports in the distributor plate are turned beyond the cut-off plate, the face of the head will effectively close these fuel ports and prevent leakage. In other words, at no time in the operation of the device is there any force tending to unseat the cut-off valve because the pressure on this plate is always in the opposite direction.

It is thought from the foregoing taken in connection with the accompanying drawings that the construction and operation of my device will be apparent to those skilled in the art and that changes in size, shape, proportion and details of construction may be made without departing from the spirit and scope of the appended claims.

I claim as my invention:

1. In a fuel feeding mechanism, a casing having a surface provided with intake and discharge ports therein, a distributor member movably mounted in said casing and engaging said surface, means including a plurality of reciprocating members controlled by the movement of said member for drawing fuel into said casing through certain of said ports and for discharging the same therefrom in predetermined charges through certain of other of said ports, control means for varying the amounts of said charges, and means for imparting a compound movement to said distributor member.

2. In a liquid injector device, a casing, an intake passage and a plurality of discharge passages for said casing, distributing mechanism including a planetary member, means for imparting a planetary movement to said member, and means for asperating liquid through said intake passage into said distributor and for discharging the same therefrom in metered charges through each of said discharge passages.

3. In a fuel feeding device, a casing, a head for said casing, a plurality of passages through said head, a distributor member having a plurality of passages therethrough, the number of passages through said head being greater than the number through said distributor member, means for imparting a compound movement to said member including a movement eccentrically of said head for causing each of the passages of said member to aline with the passages of said head in a predetermined order, and means for drawing fuel into said casing and for discharging the same through the passages in said head.

4. In a fuel injector for an internal combustion engine having a plurality of cylinders, a casing including a closure, a passage through said casing for each cylinder of said engine, means including a plurality of injector devices for discharging fuel through said passages, and means for causing each passage to be served by a plurality of said injector devices in a predetermined order.

5. In a fuel injector, a casing having a head having a raised smooth area provided with an intake and a plurality of discharge fuel passages, a distributor member movable over said area and having a plurality of fuel ports therein, resilient means for pressing said member against said smooth area, pumping means carried by said member, means for moving said distributor member to one position for receiving fuel and to another for discharging the same, said distributor in said last position having a portion extending outwardly beyond said area adjacent to the port

through which fuel is discharged whereby added pressure is applied to said member adjacent the port while it is discharging due to constant force of said resilient means on a reduced area.

5. 6. In a distributor mechanism for a fuel injector, a distributor plate member, a recess in said member, a cylinder having a head seated in said recess for forming a ball and socket-like joint, a piston for said cylinder, a cam for operating said piston, resilient means for seating said cylinder in said recess and for yieldingly forcing said piston outwardly for engaging said cam, said cylinder and member having communicating passages, and means including said piston for sucking fuel into said cylinder and for discharging the same through said passages.

7. In a fuel injector for a multi-cylinder engine, a casing, a head for said casing having a plane surface provided with a plurality of discharge ports on its under surface and an intake port for said head, a distributor plate having fuel passages, means for causing said passages to be aligned in a predetermined order with first the intake port of the casing and then with a discharge port, a pumping device for each of said fuel passages, and a variable cut-off disk for cutting-off the supply of fuel to each of said fuel passages in a predetermined order, the pressure of fuel on said plate being in a direction to continuously seat such plate during the operation of said injector, each passage being closed by the face of said head between the time of its intake and discharge.

8. In a fuel injector for use in a multi-cylinder internal combustion engine, a casing, a plurality of fuel discharging devices within said casing, means for supplying fuel to said devices, a plurality of discharge passages for said casing, one for each cylinder, and mechanism for causing said plurality of devices to discharge fuel through each of said discharge passages in a predetermined order.

9. In a fuel injector for use on a multi-cylinder internal combustion engine, a casing, a plurality of fuel discharging devices within said casing, means for supplying fuel to said devices, a plurality of discharge passages for said casing, one for each cylinder of said engine, mechanism for causing said plurality of devices to discharge fuel through each of said discharge passages in a predetermined order, and manually controlled means for regulating the interval during the suction stroke at which the fuel supply is cut off from said discharging devices.

10. In a fuel feeding device, a casing having a wall surface provided with an intake port and a plurality of discharge ports, a pumping and distributing member within said housing having a wall surface in contact with said first mentioned wall surface and provided with cooperating ports adapted to be aligned in a predetermined order with the intake and delivery ports of said casing by relative displacement of said wall surfaces, and planetary drive means for said member, whereby compound rotary and sliding motion is imparted to the wall surface of said member with respect to the wall surface of said casing.

11. In a fuel injector for internal combustion engines having a plurality of cylinders, a fuel passage for each cylinder, a plurality of pumping devices for supplying fuel to said cylinders through said passages, means for operating said devices, and mechanism for effecting a relative movement between said pumping devices and said passages for causing each of said cylinders to be

served by a plurality of said pumping devices in a predetermined order.

12. In a fuel injector, a casing having a flat face therein, a distributor member within said casing having a flat face in engagement with said flat face in said casing, said member and casing each having a plurality of openings and passages, respectively, means for revolving said member in a predetermined path over the face of said casing and for simultaneously rotating said member for bringing said openings and passages into registration in a predetermined order, and means associated with said member for metering a charge of fuel and discharging the same from said casing during registration of said openings and passages. 15

13. In a fuel feeding device, a casing, a distributor member mounted within said casing, passages through said member and casing, means for imparting a compound movement to said distributor member relative to said casing for bringing said 20 passages into register in a predetermined order, and means including plungers carried by said member for drawing fuel into said casing and for discharging the same in isolated charges therefrom through said passages during alinement, 25 and a cut-off device for controlling the amount of fuel for each charge.

14. In a fuel injector for an internal combustion engine having n number of cylinder, a distributor mechanism having p number of pumping 30 devices for supplying fuel to said cylinders said mechanism comprising a casing having a discharge passage for each cylinder for supplying fuel thereto and an intake passage for supplying fuel to said pumping devices, a distributor member having a fuel passage for each pumping device, means for moving said distributor member for causing each fuel passage to describe a path comprising a plurality of connected outwardly turned curves for causing the last-named passage 40 to register first with a discharge passage at the end of the juncture of the curves and then with the intake passage at an intermediate point in each curve, means for operating said pumping devices, and means for shifting said distributor member so that each cylinder will be supplied with fuel by a plurality of said devices, represented by the least common multiple of p and n divided by n . 45

15. In a fuel injector for an internal combustion engine having n number of cylinders, a casing, a plurality of discharge passages through said casing, one for each cylinder for supplying fuel thereto, an intake passage, a distributor member having a plurality of fuel passages therethrough, p number of pumping devices carried by said member, one for each fuel passage, means for operating said devices, means for moving said member so that each fuel passage will be brought first into register with the intake passage and then into register with one of said discharge passages in such a predetermined order that each cylinder will be supplied by a plurality of said devices with fuel, represented by the least common multiple of p and n divided by n . 55

16. In a fuel projector for a multi-cylinder internal combustion engine, a casing, a fuel reservoir in said casing, a discharge passage for each cylinder extending through said casing, an intake passage in said casing in communication with said reservoir inwardly of said discharge passages, distributor mechanism including a distributor member having fuel passages therethrough and a pumping device for each fuel passage, means for moving said plate so as to cause 70 75

- said fuel passages to align with said inlet passage and with said discharge passages for supplying fuel to said cylinders in a predetermined order, a ported plate member within said casing for delivering fuel through said intake discharge passage to said devices, and manually controlled means for regulating the interval during the suction stroke at which the fuel supply is cut off the ports in the distributor member.
- 10 17. In a fuel injector for a multi-cylinder internal combustion engine, a casing having a plurality of fuel discharge passages, one for each cylinder of said engine, for supplying fuel thereto, said passages being arranged on the circumference of a circle through a plane surface, a distributor member having a plane surface engaging the plane surface of said casing, a plurality of fuel pumping devices carried by said member, a fuel passage for each of said devices, means for rotating said member on its axis and for causing said axis to move in a circular path whereby said fuel passages will first register with said intake passage and then with said discharge passages in a predetermined order, and means for operating said pumping devices in timed relation to the movements of said member.
- 15 18. In a fuel injector for a multi-cylinder internal combustion engine, a casing having a plane surface, an intake passage for said casing, a discharge passage through said casing and plane surface for each cylinder of said engine for supplying fuel thereto, said casing having internal teeth on its side walls, a power shaft extending axially into said casing and provided with an eccentric journal, a cam surface concentric with the base of said journal, a distributor member rotatably mounted on said journal and having a flat face engaging the plane surface of said casing, a plurality of cylinder and plunger pumping devices carried by said member, means on the plungers of said pumping devices for engaging said cam surface for operating said devices, teeth formed by the outer portions of the cylinders of said pumping devices engaging the teeth on said casing whereby when said shaft is rotated said distributor member will be given a compound movement over the plane surface of said casing for bringing said pumping devices into communication first with said intake passage and then with said discharge passages in a predetermined order for supplying fuel to said engine, and means for resiliently forcing said member toward said plane surface.
- 20 19. In a liquid distributing device, a casing having a plurality of discharge passages, arranged in a circle, an intake port arranged inwardly of said discharge passages, a distributor member having a plurality of passages, a pumping device for each last-named passage carried by said member, means for moving each last-named passage alternately into registration with said port and into registration with one of said first-named passages, and means for causing each second-named passage to register in succession in a predetermined order with a plurality of said first-named passages.
- 25 20. In a fuel injector, a casing, a plurality of discharge passages for said casing, a distributor member having fuel passages therethrough, means for moving said member for selectively registering passages in said member and casing in a predetermined order, a fuel reservoir within said casing, a port for said reservoir, a plurality of fuel pumps, one for each fuel passage, said last-named passages being of substantially the same length, said means also moving said last-named passages into communication with said port in a predetermined order, and means for metering the charge of fuel supplied to each of said pumps only when said pump, reservoir and corresponding passage are in register during the suction stroke whereby substantially equal charges of fuel may be discharged through said discharge passages from said pumps.
- 30 21. In a fuel feeding device, a casing having a flat surface, a distributor member having a flat face engaging said surface and provided with fuel passages therein, a fuel reservoir, an intake fuel port in said casing in communication with said reservoir, discharge ports spaced outwardly from said intake port in said casing, and means for moving the fuel passages of said distributor member into register with said intake fuel port and with said discharge ports in a predetermined order, and pumping means carried by said distributor for withdrawing fuel from said reservoir through said intake passage and for discharging the same through said discharge ports.
- 35 22. In a fuel injector, a casing having a plurality of fuel discharge passages and an intake passage, a distributor member having a plurality of fuel ports, means for moving said distributor member so as to cause each of said ports to describe a looped path for causing each of said ports to register with one of said discharge passages when at the looped portion of its path and with said intake passage at an intermediate point, and means for sucking fuel through said intake passage and a port when the same register and for discharging the same through a port and a discharge passage when the same is brought into register.
